GLOW DISCHARGE TUBE

Maurice Ponte, Paris, France, assignor to Compagnie Generale De Telegraphie Sans Fil, a corporation of France

Application May 20, 1933, Serial No. 672,033
In France June 7, 1932

10 Claims. (Cl. 176—122)

The present invention is concerned with gaseous discharge tubes in which the variations in length of a luminous column as a function of the current flowing through the tube are used for the purpose of insuring various applications of luminous tubes such as for recording, indicators of modulation (modulation meters), etc.

Especially in this latter instance it is often desirable to be able to utilize tubes of large size designed to respond to the following conditions: 10 Assurance of sufficiently great brightness without the tube being traversed by large currents, these being conditions imposed by applications and uses of these tubes where they are called upon 15 to operate with tubes or generators of low output, and likewise by the life of the tubes, fast and copious disintegration or spattering having to be avoided therein so as to prevent undue blacking of the bulb. At the same time, the law of variation 20 of the length of the column as a function of the intensity should furthermore be as linear as possible.

In the accompanying drawing which forms part of this application, Fig. 1 shows one form of a 25 luminous discharge device. Fig. 2 represents comparative characteristic curves of devices utilizing the cathode shown in Figs. 1 and 3. Fig. 3 shows a cathode construction according to the present invention. Fig. 4 represents the characteristic curve of a device utilizing the cathode 30 shown in Fig. 3, but with the cathode wire consisting of nichrome wire, and Fig. 5 shows the complete luminous discharge device according to the invention.

35 As has been known for a long time, tubes of this kind consist of a cathode of tubular or filamentary shape mounted in the axis of a tubular bulb which comprises and contains an anode. The variations observed are those of the length 40 of the negative glow as a function of the current intensity. Fig. 1 shows a tube constructed in this manner where 1 denotes the anode and 2 the cathode extending alongside which will be observed the luminous sheath or cloak, the assembly being mounted inside a bulb 3 which has confined inside itself a gas of a suitable pressure.

However, the construction of tubes of great 50 length according to said principle is attended with and complicated by the following difficulties: In proportion as the length of the cathode rod grows which must be of sufficient diameter so as to insure rigid mounting, the current required for complete excitation of the tube grows so that 55 the latter can no longer be fed from a low-power

generator such as a small multi-electrode tube. Since at the same time the power dissipated inside the tube becomes relatively large (say, 10 watts and over) the cathode becomes subject to fast pulverization or distintegration, with the result that the tube is rendered unserviceable even after a few hours of use. Finally, the characteristic curve of the tube which represents the variations in length of the column as a function of the current flowing through the tube presents a state of saturation that is extremely marked whenever the column reaches a length near its maximum. Curve 2a, by way of example, represents the characteristic graph of a tube whose cathode has a length of 320 mm. and whose gas is at a pressure of 2.5 mm. (diameter of cathode rod being 3.5 mm.). The abscissæ in terms of milliamperes indicate the values of the current flowing through the tube, while the ordinates give the length of the negative glow in 20 millimeters. After a certain length, the negative column is found to grow but very little as the current increases, an action that is often troublesome because the useful length of the tube 25 is reduced. Tubes of reduced dimensions moreover present similar saturation phenomena. It is impossible to remedy these difficulties by reducing the pressure prevailing inside the tube seeing that the dark space would grow at the same time, and the tube would become impaired in brightness 30 or luminosity.

The present invention obviates these difficulties as hereinbefore described in that it discloses ways and means of constructing tubes of great length, of adequate brightness, low consumption and linear characteristic, this latter advantage being realizable also in tubes of smaller dimensions.

With this end in view, a first object of the invention consists in using as the cathode an insulating tube or rod or stick having the desired diameter upon which is applied a conductor whose effective surface or area is only a fraction of that of the insulating tube. A preferable mode of carrying this latter idea into practice is to form the conductor of a helix made up of a fine conductor wire wrapped around the rod at a pitch to be chosen according to practical requirements. Fig. 3 represents a cathode thus constituted, 1 being the insulating rod, and 2 the conductor wire, the end portion 3 being shown in section. Compared with a tube containing a solid cathode of similar dimensions, this scheme insures reduced consumption, at the same gas pressure. In Fig. 2 the curves 2a and 2b represent the comparative char- 55

acteristics of two similar tubes operated under similar conditions except for the cathode construction, the tube whose characteristic is represented by curve 2b being provided with the improved cathode shown in Fig. 3, while the tube whose characteristic is represented by curve 2a is provided with a cathode of the type shown in Fig. 1, which does not have a helical conductor wound about the cathode rod.

10 It will be noted that the characteristic of this tube, while improved from the viewpoint of energy consumption always involves the property of saturation. According to the second object and part of this invention, the shape or trend of the characteristic can be modified and rendered linear by using for the conductor to be wrapped about the insulator rod an element sufficiently resistant in order that the current of the tube may set up a potential difference along the cathode. Indeed, it is evident that the saturation phenomenon will be less pronounced if, instead of leaving or allowing the surface of the cathode to become equipotential in nature, a fall of potential is created thereon which grows in proportion as the cathode glow approaches the end of the cathode located opposite to or facing the anode. The most convenient way to that end consists in employing for the wire wrapped round the insulator rod a fine and resistant wire. This method is rather elastic, as it were, for, in order to modify the characteristic, it is possible to act on or change the diameter of the wire, its nature, and the winding pitch. Indeed, these factors may be chosen in a way so that the characteristic will turn out linear and assume a shape such as indicated for example in Fig. 4. This graph has been plotted for a tube similar to that for which the characteristics shown by curve 2b in Fig. 2 has been plotted, but whose cathode wire consists of a nichrome wire of 33/1000 wound with a pitch of 0.3 mm. upon a glass rod of 3.5 mm. diameter, it being understood that these figures are merely given by way of example. The resistance of the tubes obviously will be raised, but this is no inconvenience because they can be excited by tubes of high internal resistance, such as those which are known in the art as screen grid tubes.

It will be noted that in the arrangement of this invention the length of the column is directly controlled or determined by the modulated current, and that it is the variations of the current of the tube which serve to create the auxiliary differences of potential that are used to improve its characteristic. Hence, the basic principle of the invention differs from that of certain tubes used in recording work wherein use is made of an electrode on which is created a potential difference by means of an auxiliary battery with a modulation potential being superposed thereon. The two electrodes (or the single equivalent electrode) are in that case parallel and the length of the discharge is determined by the point where the voltage falls below the ignition or flash potential. The situation is wholly different in the present case and tube where the properties of the negative glows are used and where, no matter at what point the tube may be working, the voltage will never fall below the flash potential.

Fig. 5 finally represents a tube constituted in accordance with the present invention as an example of an industrial product without any limitations being imposed as regards its character. 1' denotes an insulating tube made from glass which supports the resistor wire 2' which represents the cathode conductor and which is brought

out at 4'. The anode 3' serves also to support the rod 1', the assembly being mounted inside a bulb 5' in the interior of which is the filling gas atmosphere. 6' is the anode lead-in conductor. The dimensions of the elements of the tube, for instance, may be the same as hereinbefore suggested, though it will be understood that there is no objection to use, for instance, a different pitch so as to alter the shape of or the law governing the negative glow in the case of certain practical applications.

What is claimed is:

1. A discharge device comprising a gas filled envelope and a pair of coaxially disposed electrodes between which a discharge may be passed located therein, one of said electrodes comprising a support extending linearly in said envelope and a resistance wire wound about said electrode.

2. A discharge device comprising a long tubular gas filled vessel, an anode and a cathode, the latter comprising a long insulating rod extending axially of said tubular vessel, and a high resistance wire helically wound about said insulating rod for a substantial distance thereof, the anode being coaxially disposed with respect to the cathode insulating rod.

3. A discharge device comprising a tubular gas filled vessel, an anode at one end of said vessel, a substantially lengthy insulating rod extending axially of said tubular vessel and coaxially with respect to the anode, and a nichrome wire helically wound about said insulating rod for a substantial distance thereof.

4. A glow discharge device comprising a tubular gas filled vessel, a substantially lengthy glass rod extending axially of said tubular vessel, a disc-shaped anode located at one end of said vessel and having a central opening through which one end of said glass rod is inserted for supporting the same, and a fine resistance wire helically wound about said glass rod for a substantial distance thereof.

5. A glow discharge device comprising a tubular gas filled vessel, a substantially lengthy glass rod extending axially of said tubular vessel, a disc-shaped anode located at one end of said vessel and having a central opening through which one end of said glass rod is inserted for supporting the same, and a fine nichrome wire helically wound about said glass rod for a substantial distance thereof.

6. A luminous discharge device comprising a gas filled vessel, a helically wound cathode and an anode coaxially aligned within the vessel and between which a discharge may be passed, and means for creating a potential difference along the cathode comprising a source of potential connected between the anode and one end only of the cathode.

7. A current indicating device comprising a gas filled tubular vessel, a pair of coaxially aligned electrodes therein between which a discharge may be passed, one of said electrodes comprising a substantially lengthy insulating rod and a fine wire resistance coil wrapped about the surface of said rod, and means for applying a suitable potential between the anode and one extremity of said coil, the other extremity thereof being open, whereby a potential difference is created along the surface of said rod of such value that length of the discharge is linearly proportional to the current intensity through the device.

8. A current indicating device comprising a gas filled tubular vessel, a pair of coaxially aligned electrodes therein between which a discharge

- may be passed, one of said electrodes comprising a substantially lengthy insulating rod, and means for applying a suitable potential between the anode and one extremity of said wire, the other extremity thereof being open, and a fine nichrome wire wrapped about the surface of said rod whereby a potential difference is created along the surface of said rod of such value that length of the discharge is linearly proportional to the current intensity through the device.
- 5 9. A discharge device for indicating currents conducted therethrough by the length of a glow luminous column, comprising a gas-filled tubular vessel, a pair of electrodes axially aligned therein, one of said electrodes comprising a substantially
- 10 15 lengthy insulating support and a conductor disposed thereupon, the surface of the conductor

being small as compared with the support surface, and means for applying a potential difference to said electrodes.

10. A discharge device for indicating currents conducted therethrough by the length of a glow luminous column, comprising a gas-filled tubular vessel, a pair of electrodes axially aligned therein, one of said electrodes comprising a substantially lengthy insulating support and a resistant conductor disposed thereupon, the surface of the conductor being small as compared with the support surface, and the resistance of the former being so selected that the discharge luminous length is proportional to the discharge current, and means for applying a potential difference to 15 said electrodes.
